Primary Examiner — John A Voytek(74) *Attorney, Agent, or Firm* — Dickinson Wright PLLC(57) **CLAIM**

The ornamental design for a tire, as shown and described.

DESCRIPTION

FIG. 1 is a perspective view of the tire of my design; FIG. 2 is a side elevation view of the tire of FIG. 1; FIG. 3 is a side elevation view of the tire of FIG. 1, taken from the opposite side of that shown in FIG. 2; FIG. 4 is a front elevation view of the tire of FIG. 1; and, FIG. 5 is an enlarged, partial view of the tire of my design, taken from FIG. 1.

The dash-dot-dot-line defines the boundaries of the claim. The broken line disclosure in the drawings depicts environmental subject matter forming no part of the claimed design. The tread pattern repeats over the circumferential surface of the tread.
